COMBINATION LOCK

Jack Eber, Bronx, N. Y.

Application July 22, 1939, Serial No. 285,831

17 Claims. (Cl. 70—312)

This invention relates to lock structures of the combination type adapted for the uniting and locking of a plurality of adjacent supporting members and particularly to lock structures wherein the separate locking members are in pivotal hinge-like engagement when in operative position; and the object of the invention is to provide a lock structure of the class described comprising a plurality of interfitting lock members having a lock element in slidable engagement therewith adapted in one position to retain said lock members in positive engagement and in another position to permit free separation and attachment of the lock members; a further object being to provide, in a lock structure of the class described having a slidable lock element for securing opposed lock members, a plurality of rotatable control members on said lock element having means cooperating with projecting means on said lock element for controlling the slidable movement of the locking element; another object being to provide, in a lock structure including rotatable control members cooperating with a slidable lock element, adjustable means within said rotatable members for selectively varying the relative positions in which said rotatable members cooperate with said lock element; a still further object being to provide means on rotatable control members of the class described for accurately alining the same in accordance with the predetermined adjustment thereof to cooperate with a slidable lock element, and with these and other objects in view, the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my invention are designated by suitable reference characters in each of the views, and in which:

Fig. 1 is a top plan view of one form of my improved lock shown partially in section.

Fig. 2 is a view substantially on the line 2—2 of Fig. 1 indicating one mode of attachment of the lock to a support.

Fig. 3 is a view substantially on the line 3—3 of Fig. 1.

Fig. 4 is a perspective view of one form of rotatable control member detached.

Fig. 5 is an end view of a modified form of rotatable control member.

Fig. 6 is a perspective view of the removable bushing in Fig. 5.

Fig. 7 is a perspective view of my slidable lock element detached.

Fig. 8 is a bottom plan view of the lock structure shown in Fig. 1.

Fig. 9 is a top plan view of a modified form of lock made according to my invention, and

Fig. 10 is a view substantially on the line 10—10 of Fig. 9.

In many instances where it is desirable to join and lock together adjacent, abutting or overlapping members, it has heretofore been impossible to attain the desired result in a simple, practical and economical manner, and it is the object of my invention to provide a unitary coupling and locking device which will answer this purpose and which is simple and economical in construction. My improved lock is adapted especially for use on luggage and similar containers, and when used on such articles the interengaging lock members may both be fixedly secured to adjacent supporting surfaces of the article or the structural features may be incorporated in a modified hasp construction wherein one of the interengaging lock members is movable with respect to its support. It will be understood, however, that my improved lock construction is readily adaptable for many other uses not only for locking various types of closure members but also for securing together any adjacent or abutting members to prevent undesirable separation thereof. In this connection, as will subsequently be more clearly brought out, the lock members of my improved device when in operative position are pivotally joined by a lock element, thereby providing for pivotal hinge-like movement of the lock members together with the supports.

In the drawing, I have shown my improved lock structure including two distinct forms thereof in substantially the size and proportion which might be used on articles of luggage. It will be understood, however, that this showing is for illustrative purposes only and is not intended to in any way limit the use and application of my invention to articles of luggage.

In Figs. 1 to 7 of the drawing, I have shown my improved lock as comprising a pair of interfitting lock members 10 and 11 arranged for purposes of illustration on suitable support members 12, 13, and secured thereto by suitable means as indicated by the rivets 14. The lock member 10 is provided at opposed ends of one edge portion thereof with enlarged bearings 15, 16, and is further provided intermediate the bearings 15, 16 with spaced pairs of narrow bearing projections 17, 17a. The pairs of bearing projections 17, 17a

are equally spaced from each other and from the bearings 15 and 16 providing for the arrangement of a plurality of bearing portions 18 on the opposed lock member 11 in alignment with the bearings 5 of the lock member 10 as will be clearly apparent.

Arranged within the aligned bearings 15, 16 is a transversely slidable lock element 19 which is clearly shown detached in Fig. 7. The lock element 10 comprises a series of spaced cylindrical bearings of uniform diameter, the central bearings 20 being also of uniform length while the end bearings 20a and 20b need not correspond in length. The bearings 20, 20a, and 20b are adapted 15 to engage cylindrical apertures in the bearing portions of the opposed lock members 10 and 11 as will clearly be seen at 21 in Figs. 1 and 3 of the drawing. Intermediate the cylindrical bearings 20 of the lock element 17 are reduced cylindrical portions 22 providing for the movement of the bearings 18 on the lock member 11 into engagement with the lock element by means of reduced side openings 23 in the bearing portions 18. Movement of the lock element 19 transversely of 20 the lock members 10 and 11 into the other or locked position as shown in Fig. 1 will dispose at least a portion of the cylindrical bearings 20 within the bearing portions 18 preventing subsequent separation of the lock members 10 and 11 through 25 the openings 23.

As control members for the lock element 19, I have shown a plurality of rotatable cylindrical members 24 having adjustable bushings or bearing portions 25 centrally thereof. The bushing 35 25 as well as each of the bearing portions 16, 17, and 17a are provided with transverse grooves or notches 26 adapted to receive projection members 27 on the cylindrical bearing 20 and another projection member 27a on the bearing 20a. 40 It will be apparent that the projections 27, 27a are in common alignment as are the grooves 26 in the bearing portions 16, 17 and 17a. In the locked position of the lock element 19 as seen in Fig. 1 of the drawing, the projections 27 are 45 disposed within the grooves 26 of the bearing portions 17a, and it will be apparent that in order to move the lock element into unlocked position the control members 24 must be rotatably adjusted so that the grooves 26 in each 50 of these members is in alignment with the grooves of the bearings 16, 17 and 17a. When these are properly aligned the lock element 19 may be freely moved into position to align the reduced portions 22 thereof with the openings 55 23 in the bearings 18 thereby permitting separation of the lock members. It will also be noted that when the lock element is in this position the projections 27 retain the control members 24 against rotary movement. In the construction 60 of the control member 24, as seen in Fig. 4 of the drawing, the bushing 25 is fixedly supported within the body of the control member, and it will be apparent when a projection 27 is in engagement with the groove 26 the body of the 65 control member 24 may be forcibly rotated about the bushing 25. It will be apparent, therefore, that the relative position of the groove 26 with respect to the various numerals and other insignia 28 may be changed, in other words, the 70 setting or combination of the lock may be adjusted at will by the user.

It will further be apparent, however, that in some instances it may be undesirable to have the control members 24 retained in operative alignment when the lock element is in the open

position since this would enable a person or intruder to discover the combination of the lock. If the combination were not changed as previously described, when the lock was next used the intruder would then be able to readily operate the lock as will be apparent. As a modified form of construction adapted to obviate this difficulty, I have shown in Figs. 5 and 6 a control member 24a and a bushing 25a. The control member 24a is provided with a plurality of numerals or other insignia 28a and a corresponding number of grooves or notches 29 adapted to selectively receive a projecting member or tooth 30 on the bushing 25a. The bushing 25a is preferably of solid or continuous structure having a transverse notch 26a on the inner surface thereof adapted to receive the projections 27 of the lock element. It will be apparent, as seen in Fig. 5 of the drawing, that the tooth 30 may be arranged on the bushing 25a in a position with respect to the notch 26a so that in adjusting the control member 24 the tooth 30 may be aligned with the desired numeral or insignia 28a. It should be noted in this connection that in making adjustments of the setting when this modified construction is employed, the lock element must first be removed from the lock member 10 and for this purpose the lock element 19 is provided with a removable end portion 31. The removable end portion 31 will permit withdrawal 30 of the lock element, however, only when the control members are in registering unlocked position.

As seen in Fig. 6 of the drawing, the tooth or projection 30 on the bushing 25a is preferably arranged centrally of the bushing to insure complete enclosure of the tooth by the control member. The bushing 25a is further provided on the inner surface thereof with an annular groove 32 equal in depth to the depth of the groove 26a and registering with said groove. When a bushing of this type is employed slightly greater transverse movement of the lock element 19 may be provided permitting the projections 27 on the lock element to register with the groove 32 in each of the control members, when the lock element is in unlocked position. This will provide for the rotary movement of the control members, and it will be apparent that the setting of the control members may, therefore, be changed 50 and the combination destroyed as soon as the control members have performed their intended function of permitting operative movement of the lock element.

The periphery of each control member 24, 24a is preferably provided with a series of grooves or notches 33, 33a intermediate the successive numerals or insignia 28. These notches are in turn operatively engaged by suitable spring members 34 secured to the underside of the lock member 10. The spring members 34 preferably permit rotary movement in one direction while preventing rotary movement in opposed direction; the important function being to properly align the numerals or insignia 28 by positive engagement 65 of the spring members with the grooves 33, 33a. As a further aid in properly aligning the numerals an indicating means, such for example as the arrow, seen at 35 in Fig. 1, is provided on one or both of the bearings 15, 16.

In Figs. 9 and 10 of the drawing, I have shown a slightly modified form of construction including lock members 10a, 11a, a lock element 19a and control members 24a. The construction of the parts in this modified form of lock corre- 75

sponds substantially with the structures previously described in connection with Figs. 1 to 8. The essential difference in the modified form is that the lock member 11a is pivotally secured as at 36 to a hinge plate 37 which in turn may be secured to the surface of a desired support. The openings 23a in the bearing portions 18a of the hinge member 11a differ from the openings 23 in the previously described construction in that they are arranged to permit disengagement of the lock members by the swinging movement of the lock member 11a. In other words, the line of motion in coupling and uncoupling the lock members shown in Figs. 9 and 10 is substantially at right angles to the line of motion in the similar operation of the device shown in Figs. 1 and 2. It will of course be apparent that any other direction of movement might be provided by suitably arranging the openings 23a on the lock member 11a to facilitate joining and locking together adjacent members having predetermined angularly arranged surfaces.

As shown in Figs. 9 and 10 of the drawing, the lock member 11a corresponds to a hasp such as is normally used on articles of luggage, and it will be apparent in this connection that a spring 38 is preferably included in the pivot portion 36 to provide for the automatic disengagement of the lock members when the lock element 19 is moved into the unlocked position.

When the lock members of my improved device are in operative engagement, it will be apparent that the members are in reality pivotally coupled by the lock element and in effect the lock members are adapted to function as hinge butts pivotally movable about the lock element as a pintle. This feature readily adapts my device for use as more than a mere means for locking together adjacent or abutting supports. By way of illustration, it will be apparent that one or more of my devices may be employed as hinges on closure members having other locking means thereon. A closure member equipped with my devices as hinges could then be opened by the party knowing the lock combination in emergencies such for example as the loss of a key to the conventional lock means for the closure. The particular uses to which my improved lock and hinge device can be put are too numerous to mention. It should be understood, however, that I do not limit myself to the particular adaptations above mentioned but may employ my improved structure wherever the circumstances would make its use practical.

The various parts of my device may be fashioned by any of the conventional forming and machining methods and any suitable materials may be used to give the required strength and properties to the device. The control members 24, 24a may, of course, be fashioned from a unitary body having the desired arrangement of the groove 26 or the groove 26a and 32 therein. The construction as shown in the drawing, however, is probably more practical from a commercial standpoint since with each of the modifications a standard body portion for the control member may be formed as well as a standard bushing, and the adjustment of the control member may then be obtained by assembling the two parts in the desired manner. Forming the control members as unitary bodies on the other hand would necessitate the making of a different control member to correspond with each of the different numerals or insignia 28, 28a. A further advantageous feature of the two part construction is

that metallic wear-resisting material may be employed for the bushing whereas the body portion of the control member may be fashioned from suitable plastic material. The wide range of colors obtainable in the plastic materials would provide for the enhanced appearance of the lock as well as making the numerals or insignia more legible.

It should also be noted that any number of control members 24, 24a may be employed, and it will further be apparent that each of the control members may have any desired number of numerals or other insignia 28. For example in a more complicated lock, letters or other symbols could be employed at 28 to provide a number of indicating panels greatly in excess of the ten panels shown in the drawing. In such a construction, means would of course be provided for selectively adjusting the bushing and alining the same with the desired indicating panel.

Having fully described my invention, what I claim as new and desire to secure by Letters Patent, is:

1. In a combination lock including opposed lock members and a lock element having limited transverse slidable movement with respect to said members into two terminal positions, said lock element being adapted in one terminal position thereof to secure the lock members together, while in the other terminal position thereof permitting free coupling and uncoupling of the lock members, means rotatably mounted on said lock element for regulating the transverse movement of said element.

2. In a combination lock including opposed lock members and a lock element having limited transverse slidable movement with respect to said members into two terminal positions, said lock element being adapted in one terminal position thereof to secure the lock members together, while in the other terminal position thereof permitting free coupling and uncoupling of the lock members, means rotatably mounted on said lock element for regulating the transverse movement of said element, and said last named means comprising control members having transverse grooves adapted in predetermined positions thereof to fall in alinement with corresponding grooves in one of said lock members.

3. In a combination lock including opposed lock members and a lock element having limited transverse slidable movement with respect to said members into two terminal positions, said lock element being adapted in one terminal position thereof to secure the lock members together, while in the other terminal position thereof permitting free coupling and uncoupling of the lock members, means rotatably mounted on said lock element for regulating the transverse movement of said element, said last named means comprising control members having transverse grooves adapted in predetermined positions thereof to fall in alinement with corresponding grooves in one of said lock members, and projecting members in longitudinal alinement on said lock element registering with said grooves.

4. A lock device including opposed lock members having interfitting bearing portions, a lock element slidably movable through said bearings, said lock element being supported by one of said lock members and having reduced portions at longitudinally spaced intervals adapted in one position of said lock element to register with reduced openings in the bearings of the opposed lock member thereby facilitating separation of

being formed in independent bushings detachably supported in different positions of rotary adjustment with respect to indicating panels formed on the periphery of said wheels.

5 13. A combination controlled mechanism of the class described for joining opposed members, said mechanism including a plurality of protruding parts on one of said members, a lock element slidable in said parts, combination control means on said lock element adapted in predetermined positions only thereof to permit movement of said element, protruding means on the other of said members interfitting with said protruding parts of the first named lock member and registering with said lock element, and cooperating means on said last named protruding means and lock element providing for coupling and uncoupling of said lock members in the unlocked position only of said element.

10 14. A combination lock of the character described comprising an elongated lock element movable longitudinally of its axis, a pair of lock members having parts spaced longitudinally of said element, said lock element being supported against displacement from said part of one lock member and operatively engaging said part of the other lock member in the movement thereof, said lock element being adapted in one position only of adjustment to provide separation of said parts transversely to the axis of said element, and means supported on said lock element and movable with respect thereto for controlling the separation of said parts.

15 15. A combination lock of the character described comprising an elongated lock element movable longitudinally of its axis, a pair of lock members having parts spaced longitudinally of said element, said lock element being supported against displacement from said part of one lock

member and operatively engaging said part of the other lock member in the movement thereof, said lock element being adapted in one position only of adjustment to provide separation of said parts transversely to the axis of said element, means supported on said lock element and movable with respect thereto for controlling the separation of said parts, one of said lock members being fixedly secured to a support, and the other of said lock members being pivotally secured to an opposed support.

16. A combination lock of the character described comprising two relatively movable lock members, a lock element movably supported in and retained against displacement from one member, the other member being movable into the path of movement of said element and engaged by said element in retaining said members against separation, a plurality of rotatably adjustable characterized discs supported on said element, and cooperative means between the discs and element controlling movement of said element into open position to provide separation of said members.

17. In a combination lock mechanism employing two lock parts and combination discs controlling separation of the parts, a lock pin supported in one part and forming an axis about which said discs are rotated, means on the pin preventing movement thereof in said parts from a locked to an unlocked position except upon proper setting of said discs, said pin engaging the other of said parts when in locked position to retain the parts against separation, and said pin having a recessed portion brought into registering alignment with the last mentioned part in the movement of the pin into unlocked position to provide separation of said parts.

JACK EBER.
